UNITED STATES PATENT OFFICE.

ALEXANDER YOUDELMAN, OF NEW YORK, N. Y.

TIP-ATTACHING IMPLEMENT.

1,312,292.

Specification of Letters Patent.

Patented Aug. 5, 1919.

Application filed April 10, 1919. Serial No. 288,969.

To all whom it may concern:

Be it known that I, ALEXANDER YOUDELMAN, a citizen of the United States, and a resident of the city of New York, borough 5 of Manhattan, in the county and State of New York, have invented a new and Improved Tip-Attaching Implement, of which the following is a full, clear, and exact description.

10 The object of the invention is to provide a new and improved implement or hand tool more especially designed for attaching metallic tips to the ends of strings such as are used for lacing shoes, corsets and like 15 articles, and arranged to enable the user to readily replace a worn out or broken tip by a new one. Another object is to enable the user to properly manipulate the tool without requiring undue physical exertion.

20 With these and other objects in view, the invention consists of certain novel features of constructions, as hereinafter shown and described and then specifically pointed out in the claims.

25 A practical embodiment of the invention is represented in the accompanying drawings forming a part of this specification, in which similar characters of reference indicate corresponding parts in all the views.

30 Figure 1 is a sectional side elevation of the tip attaching implement, the section being on the line 1—1 of Fig. 2;

Fig. 2 is a plan view of the same;

35 Fig. 3 is a cross section of the same on the line 3—3 of Fig. 1;

Fig. 4 is an enlarged sectional side elevation of the jaws in closed position and with the tip fastened in place to a string;

40 Fig. 5 is a sectional side elevation of a modified form of the tip attaching implement arranged for simultaneously affixing two tips to the ends of a string;

Fig. 6 is a perspective view of a tip blank; and

45 Fig. 7 is a perspective view of a tip in position on the end of a shoe string.

The implement or tool, comprises essentially the fixed jaw 10 and a movable jaw 11, of which the fixed jaw 10 is in the form of 50 a steel plate 12 having at its front end a return bent member 13 parallel to the plate 12, the bend forming the jaw 10. The plate 12 and its return bent member 13 form a guide for the front end of the movable jaw 11 to slide in, the front end of the movable jaw 11 being provided with a concave recess 14

which coacts with the inner concave face of the jaw 10 formed by the bend, as above explained. It is understood that the jaws 10 and 11 are adapted to receive between them 60 a U-shaped metal clip blank 17, into which is inserted one end 18 of a string 19 to be provided with the tip 20. On moving the jaw 11 toward the fixed jaw 10 the tip blank 17 is closed around the end 18 of the string 65 19 thus providing the latter with the tip 20.

The fixed jaw plate 12 is fastened by screws 25 to a frame 26 provided with an integral handle 27, the frame 26 having two side members 28 between which is confined the 70 movable jaw 11. The side members 28 of the frame 26 are connected with each other at their front end by a cross-bar 29 which forms a support for the return bent member 13 of the jaw plate 12.

75 The movable jaw 11 is preferably made in the form of a plate provided at its rear end with an angular lug 30 extending downwardly into a recess 31 formed in the pivotal end 32 of a hand lever 33 having its pivot 80 34 attached to the side members 28 of the frame 26. The handle 33 is disposed opposite the handle 27 and a spring 35 is interposed between the said handles 27 and 33 to normally hold the lever 33 and consequently the movable jaw 11 in the open 85 position illustrated in Fig. 1. The lower end of the handle 33 is provided with a bend 36 in which screws a stop screw 37 adapted to abut against the free end of the 90 handle 27 to limit the closing movement of the lever 33 and that of the movable jaw 11. It is understood that by adjusting the stop screw 37 the forward movement of the jaw 11 is limited to insure a proper attaching 95 of the tip 20 to the end 18 of the string 19 according to the thickness of the said string. From the foregoing it will be seen that by the arrangement described the tip attaching implement or tool is composed of very few 100 parts arranged to properly coact without danger of getting out of order.

In the modified form shown in Fig. 5, the movable jaw 50 is provided at the under side with a recessed shoulder 51 which coacts with the end of the return bent member 52 of the plate 53 forming the fixed jaw 54 with which coacts the forward end 55 of the jaw 50. The plate 53 is fastened by screws 56 to the frame 57 having a handle 58. The 110 under side of the movable jaw 50 is provided with rack teeth 60 in mesh with a toothed

segment 61 formed on a movable lever 62 fulcrumed at 63 on the frame 57. By moving the lever 62 toward the handle 58, the jaw 50 is moved forward to permit of attaching two tips simultaneously to the ends of a string, it being understood that one tip is attached by the coaction of the return bent member 52 and the shoulder 51. The return bent member 52 slidingly engages a crossbar 64 forming part of the frame 57.

Having thus described my invention, I claim as new and desire to secure by Letters Patent:

1. A tool of the type described, comprising a pair of coacting fixed and movable jaws, the said fixed jaw being in the form of a plate having at its forward end a return bent member forming with the plate a guide for the said movable jaw, a frame provided with a handle and on which the said plate is secured, the frame having a crossbar forming a bearing for the said return bent member, and means mounted on the said frame to actuate the said movable jaw.
2. A tool of the type described, comprising a pair of coacting fixed and movable jaws, the said fixed jaw being in the form of a plate having at its forward end a return bent member forming with the plate

a guide for the said movable jaw, a frame provided with a handle and on which the said plate is secured, the frame having a crossbar forming a bearing for the said return bent member, a spring-pressed lever fulcrumed on the said frame and disposed opposite the said handle, and coacting means connecting the lever and the movable jaw to actuate the latter on alternately pressing and releasing the lever.

3. A tool of the type described, comprising a pair of coacting fixed and movable jaws, the said fixed jaw being in the form of a plate having at its forward end a return bent member forming with the plate a guide for the said movable jaw, a frame provided with an integral handle and on which the said plate is secured, the frame having a crossbar for the said return bent member to rest on, the said movable jaw being in the form of a plate having its forward end extending between the plate and its return bent member, the sides of the movable jaw being confined between the sides of the frame, the said movable jaw having a lug, and a spring-pressed lever fulcrumed on the said frame and provided with a notch engaged by the lug of the said movable jaw.

ALEXANDER YOUDELMAN.

Copies of this patent may be obtained for five cents each, by addressing the "Commissioner of Patents, Washington, D. C."
